UNITED STATES PATENT OFFICE.

EDWARD A. FRANKLIN, OF AUSTIN, TEXAS.

VAPOR-BURNER.

No. 813,494.

Specification of Letters Patent.

Patented Feb. 27, 1906.

Application filed June 3, 1905. Serial No. 263,605.

To all whom it may concern:

Be it known that I, EDWARD A. FRANKLIN, a citizen of the United States, residing at Austin, in the county of Travis and State of Texas, have invented a new and useful Vapor-Burner, of which the following is a specification.

This invention relates to vapor-burners, and more particularly to that class of vapor-burners which are especially adapted for the consumption of crude oil and similar heavy hydrocarbons, although the use thereof is not necessarily limited in this respect.

Among the objects of the present invention are to simplify and improve the construction and operation of this class of burners, to provide simple and improved means for regulating and deflecting the flame, and to present a device which shall possess superior advantages in point of simplicity, durability, and general efficiency.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of the invention, it being, however, understood that no limitation is necessarily made to the precise structural details therein exhibited, but that the right is reserved to any changes, alterations, and modifications to which recourse may be had within the scope of the invention and without departing from the spirit or sacrificing the efficiency of the same.

In said drawings, Figure 1 is a vertical transverse sectional view of a hydrocarbon-burner constructed in accordance with the principles of the invention, the same being taken on the plane indicated by the line 1 1 in Fig. 3. Fig. 2 is a sectional detail view taken on the plane indicated by the line 2 2 in Fig. 1. Fig. 3 is a top plan view with parts broken away for the purpose of exposing the subjacent construction. Fig. 4 is a perspective detail view showing the burner-tip inverted. Fig. 5 is a perspective detail view showing the deflector detached.

Corresponding parts in the several figures are indicated throughout by similar characters of reference.

The form of the invention herein shown is especially adapted to cooking stoves and

ranges, it being understood that modifications whereby the invention is adapted to be used in connection with heating-stoves of various patterns are within the range of the 60 skill of the ordinary mechanic.

The device includes a hollow casting or reservoir 1, formed with a conical projection 2 upon its upper side, the sides of said conical projection being dished, so that an annular groove 3 will be formed at the base of the cone. The casting or member 1 has a cored chamber 4, constituting a reservoir, into the upper part of which at opposite sides are threaded pipes 5 and 6. The casting 1 is 70 also formed with an exterior-grooved flange 7, forming an annular gutter 8.

The casting or, as it may be properly termed, the "vaporizing-chamber" is connected, by means of brackets 9, with the under side of a supporting-plate 10, which has been shown circular in shape, so that it may be supported in or above one of the griddle-holes 11 in an ordinary stove-top, a portion of which has been shown at 12. The pipes 5 and 6 are extended through perforations 13 in the plate 10 and are provided above said plate with elbows 14 15. The elbow 14 of the pipe 5 is connected, by means of a conducting-pipe 16, with a storage-tank 17, said 85 pipe 16 being preferably provided with a valve 18, whereby the flow of the liquid hydrocarbon may be regulated. The elbow 15 has connected therewith a cap 19, into the under side of which is threaded a nozzle 20, 90 constituting the burner-tip and which is preferably provided with a non-circular portion affording a wrench-seat, enabling it to be readily detached for the purpose of cleaning it or replacing it with a new one when necessary. The supporting-plate 10 is provided with a central opening 21, disposed directly beneath the nozzle or burner-tip, which latter is directed toward the apex of the cone 2.

Mounted for rotation upon the cap 19 is a 100 deflecting member 22, which consists simply of a metallic strip or band bent to form a sleeve 23, encircling the cap and having a slot 24 engaging the tip or nozzle 20. The ends of the metal strip forming the sleeve 23 are 105 connected by means of a clamping-bolt 25, having a nut 26, whereby the device is secured for rotation upon the burner-cap, and the ends of the strip are extended in opposite directions, forming a handle 27, whereby the 110 device may be manipulated to turn or rotate the sleeve, and a deflecting-leaf 28, which by

partially rotating the sleeve may be extended beneath the burner-tip or moved to one side of the latter, as may be desired.

- The opening 21 in the plate 10 is surrounded by an annular flange 29, upon which is mounted an oscillatory slide 30, which rests upon the plate 10 and is provided with perforations 31, adapted to register with apertures 32 in the said plate 10, said apertures 32 being provided with inner walls 33, which are inclined in the direction of the central aperture. The oscillatory sliding member is provided with pins or studs 34, extending through segmental slots 35 in the plate 10, said slots being concentric with the axis upon which the slide 30 oscillates, the function being simply to limit the movement of said slide. The latter, as will be readily seen, may be turned so as to obstruct the openings 32, or it may be adjusted so as to uncover said openings wholly or in part, thus regulating the admission of air needed for immediate admixture with the vapor generated by the burner to form a readily-combustible gas. It will of course be understood that the major part of the air needed to support combustion will be furnished through the draft-openings in the stove in connection with which the device is used.
- In the operation of this device the liquid fuel is permitted to flow from the tank through the conducting-pipes 16 and 5, through the chamber 4, and through the pipe 6 into the cap 19, from which it is discharged through the nozzle or burner-tip 20 upon the apex of the cone 2. When the groove 3, surrounding the base of the cone, has been partly filled, the supply may be turned off, and the oil in the groove 3 may be ignited by dropping a lighted match through the aperture 21. Overflow from the groove 3 will be caught in the channel 8 and will be ignited, thus assisting in quickly heating the generator 1. When the latter has been thoroughly heated, the oil contained in the chamber 4 will be vaporized and rise through the tube 6, being discharged downwardly through the nozzle 20 in the form of vapor, which will be instantly ignited, the flames being deflected laterally by the sides of the cone, as indicated by arrows in Fig. 1 of the drawings. The valve 18 is now adjusted to keep up constant flow of oil as long as it shall be desired to keep the burner going, it being extinguished by merely cutting off the supply of fuel. If it is desired to minimize the consumption of fuel, the deflector 28 is adjusted approximately in the position shown in Fig. 2 of the drawings—that is, extending beneath the burner-tip, so that the vapor emerging through the latter shall be deflected to one side. When the deflector is in this position, it is found that a very intense heat may be produced with a minimum consumption of oil, so small, in fact, as to be insufficient to support combustion when the deflector is moved out of the path of the vapor issuing from the nozzle-tip.

From the foregoing description, taken in connection with the drawings hereto annexed, the operation and advantages of this invention will be readily understood by those skilled in the art to which it appertains. The general construction is simple and inexpensive, and a burner constructed in the manner herein shown and described is applicable to and adapted to be successfully used in connection with cooking stoves and ranges of various sizes, the supporting-plate 10 being adapted to be supported in the griddle-holes or upon the top plate of the stove, as the case may be. The heat may be easily regulated, and a very intense heat may be generated with a small consumption of fuel.

Having thus described the invention, what is claimed is—

1. A casting cored to form a generating-chamber and having on its upper side a conical projection with dished walls forming an annular channel surrounding the base of the cone, suspending means for said casting, a feed-pipe entering the generating-chamber, and a discharge-pipe connected with the generating-chamber and extending above and discharging in the direction of the cone.

2. A generator having upon its upper side a cone, and an annular channel surrounding the base of the cone; suspending means for the generator; a supply-pipe threaded into one side of the generator; an exit-pipe threaded into the opposite side of the same and having a laterally-extending terminal cap; and a nozzle or burner-tip the outer end of which forms a wrench-seat and the inner end of which is threaded into said cap and directed toward the apex of the cone.

3. A plate having an aperture, a generator suspended beneath said aperture and having upon its upper side a conical projection and a channel surrounding the base of the cone an annular overflow-gutter formed exteriorly upon the generator, a supply-pipe connected with one side of the generator, an exit-pipe connected with the opposite side of the generator and extending through the supporting-plate, a terminal cap connected with and extending laterally from the exit-pipe, and a nozzle or burner-tip threaded into said cap and directed toward the apex of the cone.

4. A burner-cap, a nozzle extending radially from said cap, a sleeve encircling the cap and having a slot engaging the nozzle, and a deflecting member connected with said sleeve.

5. A burner-cap, a tip or nozzle radiating therefrom, a sleeve encircling the cap and having a slot engaging the tip, and leaves extending in opposite directions from said sleeve and constituting respectively a deflector and a handle.

6. A burner-cap, a tip or nozzle radiating

therefrom, a strip encircling the cap to form a sleeve and having a slot engaging the tip, and a clamping-bolt connecting the parts of the strip constituting the sleeve; the ends of

5 said strip being bent in opposite directions to constitute respectively a handle and a deflector.

7. The combination with a burner-cap having a radiating tip, of a slotted strip bent 10 upon the cap to form a sleeve and laterally-extending members constituting respectively a handle and a deflector, and connecting

means for clamping the sleeve for rotation upon the cap; the slotted portion being in engagement with the tip to limit the extent 15 of rotation of the sleeve.

In testimony that I claim the foregoing as my own I have hereto affixed my signature in the presence of two witnesses.

EDWARD A. FRANKLIN.
